Burt E Taylor

UNITED STATES PATENT OFFICE.

BURT E. TAYLOR, OF MOUNT VERNON, NEW YORK, ASSIGNOR OF ONE-THIRD TO
S. FREDERIC TAYLOR, OF NEW YORK, N. Y., AND ONE-THIRD TO WILLIAM H.
HOWARD, OF PORT CHESTER, NEW YORK.

SEALING DEVICE FOR JARS.

1,407,008.

Specification of Letters Patent. Patented Feb. 21, 1922.

Application filed April 25, 1919. Serial No. 292,555.

To all whom it may concern:

Be it known that I, BURT E. TAYLOR, a citizen of the United States, residing at Mount Vernon, Westchester County, State 5 of New York, have invented certain new and useful Improvements in Sealing Devices for Jars, of which the following is a full, clear, and exact description.

This invention relates to improvements 10 in sealing means for jars more especially preserve jars. The object of my invention is to provide a means whereby the vacuum can be broken, thereby rendering the operation of removing the tops of a preserve jar 15 an easy matter. It is a well known fact that the tops of jars have to be pried off, or slightly raised along a portion of the edge thereof, in order to break the vacuum. Preserve jars are usually sealed while 20 heated, that is to say, the matter to be preserved is placed in the jars, and the jars completely filled while the jars are hot and also while the matter to be preserved is hot; in fact the jars are usually placed in 25 hot water and filled, the jars being sealed while heated; hence all air is excluded. After the jars have cooled off and the tops are to be removed, say for instance some months later, the tops of the jars have to 30 be pried off, or as has been stated, slightly raised along a portion of their edges to break the vacuum. I am aware that means have been provided to facilitate the removal of these tops, such for instance as providing 35 the tops with openings therethrough, said openings being covered by a rubber pad held in place by yieldable resilient strips. One of the objections to this form of device is that the openings become plugged 40 with the candied syrup within the jars or else the rubber pads become vulcanized and leak or else plug the openings. One of the objects of my invention is to prevent the candied syrup from plugging the opening 45 or to prevent the plugging of the opening from any cause.

In the accompanying drawing, I have illustrated means which I prefer to employ to carry out my invention.

50 Referring to the drawing—

Fig. 1 illustrates an embodiment of my invention;

Fig. 2 is an enlarged cross sectional view, the section being taken on a line 2—2 in Fig. 1;

55

Fig. 3 illustrates a modified form of my improvement; and

Fig. 4 is an enlarged detail view of the vacuum relief valve employed in connection with the modified form of my invention. 60

In the accompanying drawing, a portion 65 of a preserve jar is indicated by 5 having a neck 6, carrying threads 7 to receive the threaded body portion 8 of a securing ring 9 to maintain the top 10 of the jar in position. Between the top 10 and edge 11 of the jar, a gasket 12 is located, said gasket being usually made out of rubber. The function of the ring 9 is to force the top 10 against the gasket 12, which in turn is 70 forced against the edge 11 of the neck 6 to maintain the jar air tight, after matter to be preserved is placed within the jar 5. As has been stated, the top 10 will be placed in position, also gasket 12, and the securing ring 9 applied while the matter within 75 the jar is in heated condition, and as the jar will be completely filled, there will be no air within the jar after it has cooled off and the vapors within same have condensed. In other words, the contents of the jar will be under vacuum after it has cooled off; hence the top 10 will have considerable pressure thereupon, and in order to remove same considerable force is required unless the vacuum is broken. To 80 break the vacuum, in order to render the top 10 easily removable, I provide special means in the form of an opening 13 through the top 10, a valve 14 therefor and a yieldable 85 resilient strip or spring 15, the ends 16 of which, in this instance, are caught under the flange 17 of the securing ring 9. The valve 14 (in this instance) consists of a stem 18, which passes through the opening 13, carried by the strip 15, and a yieldable pad member 19, preferably of rubber, which is considerably larger than the diameter of the opening 13. The object of the stem 18 is 90 to entirely fill the opening 13 to prevent syrup from within the jar to enter same and become candied, thereby plugging the said opening, and also to assist the pad 19 in 95 performing the function of preventing air

100

from prematurely entering the jar through the opening 13. The function of the spring 15 is to force the pad tightly against the top of the jar to seal the opening 13, but 5 the stem 18 assists the pad to a large extent as it completely fills the opening 13; hence the chances of leakage are greatly lessened more so than if the stem was not employed. The spring 15 and its valve 14 will be placed 10 in position before the ring 9 is applied, and the ends 16 of the spring will be positioned as indicated by dotted lines (Fig. 1). When the ring is applied, the ends of the spring will be forced down thereby forcing the pad 15 19 firmly against the top. When the top is to be removed, it is but necessary to remove ring 9 and pull the spring 15 and valve 14 off the top 10, after which air will flow in to the jar through opening 13. The 20 top 10 may now be easily removed.

Fig. 3 illustrates a jar 20 having a top 21 which is held by a clamping device instead of a retaining ring, said clamping device being the usual hasp 21 connected at 25 its end to a lever device 22 which in turn is pivotally connected to a supporting band 23 carried by the jar 20. This form of clamp is well known and needs no further description. In this form of my invention, 30 I employ a valve mechanism 24 consisting of a carrier 25 provided with a pin 26 to enter and fill the opening 27 in the top 21. The carrier also supports a pad 26^a, preferably of rubber. The valve 24 performs 35 the same function and acts in the same manner as valve 14 in the form illustrated in Fig. 1, excepting pressure is supplied by a clamp instead of a spring.

The carrier 25 projects beyond its pad 40 26^a in order that the valve can be pried off without injuring the pad.

Having described my invention, what I claim is:—

1. In combination with a cover or top for jars, having an opening therethrough, a 45 valve consisting of a yieldable pad to cover said opening, and a stem to enter said opening together with means to force the pad firmly against the said cover or top, said valve and cover being arranged to be removed from said cover simultaneously.

2. The combination of a jar, a top or cover for same having an opening, and a ring member to secure the cover to the jar, a resilient strip, a stem carried thereby to 55 enter and approximately fill the opening in said cover, a yieldable pad member carried by the strip and surrounding the strip and stem at the point of securement of the stem to the strip, the ends of the resilient strip 60 being arranged for insertion between the cover of the jar and securing ring therefor, whereby said pad will be forced against the cover when said ring is screwed down.

3. In combination with a jar having a 65 top provided with an opening, and means to secure the top to the jar, a valve mechanism to close said opening, consisting of a carrier provided with a pin to enter the opening in the top, and a yieldable pad 70 carried by the carrier and surrounding said pin at the point of securement of the pin to the carrier, said carrier extending beyond the ends of the pad to provide means to enable the valve to be pried off the top 75 of the jar without injuring the pad.

Signed at New York city, N. Y. this 24 day of April 1919.

BURT E. TAYLOR
